UNITED STATES PATENT OFFICE

MAX J. ISAACSON, OF BROOKLYN, NEW YORK

DISENGAGEABLE FASTENER

Application filed April 25, 1930. Serial No. 447,341.

This invention relates to an improved disengageable fastener which may be used in many places as, for instance, on boats, in dwellings, etc. for connecting curtains and other articles and wherever two articles are to be disengageably connected together, the structure being such that the parts may be quickly engaged and disengaged.

Another object of the invention is to provide a disengageable fastener for curtains or other objects wherein a slide fastener of the zipper type is used in association with certain members in association with a curtain rod or other article.

A further object, more specifically, is to provide a disengageable fastener for curtains or other objects wherein members forming loops or encircling members are connected to the article and these members disengageably secured together by a slide fastener of the zipper type arranged so that the sliding member may be disengaged from one part of the fastener so that a complete separation of the encircling members may be secured.

In the accompanying drawings—

Figure 1 is a fragmentary view of a boat showing part of a cabin with a curtain held in place by an embodiment of my invention;

Figure 2 is an enlarged embodiment of the invention arranged similar to that shown in Figure 1;

Figure 3 is a top view of the bracket shown in Figures 1 and 2;

Figure 4 is a sectional view through Figure 2 on lines 4—4;

Figure 5 is a view similar to Figure 4 but showing the parts in different position;

Figure 6 is an enlarged detailed fragmentary sectional view through Figure 1, approximately on the line 6—6.

Referring to the accompanying drawings by numerals, 1 indicates a boat of any kind having a cabin 2 and an awning structure 3. In order to enclose the awning structure one or more curtains 4 are provided. In order to quickly mount and demount this curtain an embodiment of the invention is used at the upper and lower edges. The invention has been shown on curtain 4 associated with a boat 1 merely for the purpose of illustration,

but it will be understood that the invention may be used in many other places.

Figure 2 is, in effect, the interior view of one of the lower corners of curtain 4 and bracket 5. Coacting with bracket 5 is a similar bracket 6, and coacting with this bracket and other parts are brackets 7 and 8. Preferably all of these brackets are identical in construction, as shown in Figures 2 to 5 inclusive. As illustrated, bracket 5 is formed with a depending apertured portion 9 adapted to receive screws or other fastening means 10, whereby the bracket may be secured to some part of the boat 1. Bracket 5 at the upper end is provided with a tubular section 11 having a slot 12 extending from one end.

A double flanged sleeve 13 is rotatably mounted in the section 11, said sleeve having a notch or slot 14 adapted to be brought into registry with the slot 12, as shown in Figure 5, when the end of rod 15 is to be inserted or removed. Sleeve 13 carries a pin 16 which projects through the slot 17 as shown in Figure 3, said pin preferably having an enlarged head 18 whereby it may be easily actuated for swinging the sleeve 13 to the position shown in Figure 4. By this arrangement of brackets the rod 15 may be readily applied or removed at any time. Coacting with rod 15 are means for connecting the rod with a curtain or other article. As shown in Figures 2 and 3 of the drawings, the article 4 has connected therewith the flexible members or stringers 19 and 20.

These stringers are made extra wide so that an appreciable part of one edge thereof may be secured by cement or other means to the article 4, as shown in Figure 6, and yet leave ample room for the reception of the rod 15.

The stringers 19 and 20 are provided with the usual beads to which the interlocking plates or members 22 and 23 are secured. These interlocking members coact with slide 24 to form a slide fastener which is disclosed as of the zipper type. In this way the slide fastener coacts with the flexible members 19 and 20 and with the article itself to provide an enclosure (Fig. 6) whereby the rod 15 or other article may be enclosed. This provides

an effective connection with the curtain or

other article and said connection as shown in Figure 2 is intermediate the ends of the article.

Usually in slide fasteners of the zipper type there are two abutments or stops 25 at one end, and this structure may be used in the present invention, if desired. Where there are two stops 25, namely, one on the encircling member 19 and another on the encircling member 20, slide 24 may be moved down to these stops and then sleeve 13 rotated. After this has been done rod 15 is lifted out of the bracket 5 and then the curtain 4, and encircling members 19 and 20, are moved to the left, as in Figure 2, until disengaged from rod 15.

However, preferably the attachment is made with only one abutment 25 and with a thin section 26 opposite abutment 25, whereby the slide fastener 24 may move off of section 26 so that member 20 is completely disengaged from the encircling member 19. As illustrated in Figure 1, there is a rod 15 at the bottom of curtain 4 and, if desired, a similar rod 15' at the upper part, whereby the curtain 4 may be completely removed at any time. In applying the curtain it is only necessary to move the encircling members 19 and 20 until they encircle the rod 15 near bracket 5. The slide 24 is then slipped on to the flat or thin section 26, and then on to the interlocking plates 22 and 23. After this has been done the slide 24 may be quickly moved to the opposite bracket, whereupon all of the members 22 and 23 will be locked and the curtain secured to the rod 15. The same action takes place in regard to rod 15'.

Where the thin section 26 is used the bracket 5 may be eliminated and any suitable bracket employed for supporting rod 15, but where there are two abutments 25 bracket 5 will be essential, as the end of rod 15 must be moved out of the bracket in order to slide the end portion of the fastener and encircling members 19 and 20 off one end of the rod.

What I claim is:

1. A device of the character described, including a substantially flat article, a zipper fastener structure provided with a pair of encircling flexible strips, and means for connecting one edge of each strip to said article intermediate its length whereby said strips and that part of said article between said strips are adapted to encircle a bar for connecting said article to the bar.

2. A device for securing a substantially flat article to a bar including, a pair of flexible encircling members one edge of each of said members being secured to said article intermediate the length of the article, said members being positioned to partly encircle said bar and disengageable fastening means for disengageably securing the other edges of said encircling members together whereby

part of said article, said encircling members and said fastening means are adapted to encircle said bar for connecting said article to said bar.

3. The combination with a substantially flat flexible article of means for securing the same to a rod comprising a pair of flexible members each of said members having one of its longitudinal edges secured to said article, disengageable fastening means connected to the opposite edges of the respective flexible members, and means for causing said disengageable fastening members to be interlocked.

Signed at New York in the county of New York and State of New York this 23rd day of April, A. D. 1930.

MAX J. ISAACSON.
